UNITED STATES PATENT OFFICE.

ELMER E. LANDON, OF SANTA MONICA, CALIFORNIA.

RECEPTACLE.

Application filed December 23, 1925. Serial No. 77,300.

This invention relates to receptacles especially adapted for receiving rolling pins and the like while not in use.

Briefly stated, an important object of the invention is to provide a receptacle of the character specified having simple means whereby a rolling pin is automatically locked in place within the receptacle upon its insertion therein and is partly ejected from the receptacle upon the manual actuation of the locking means so as to permit of the complete manual removal of the rolling pin.

Another aim of the invention is to provide a receptacle of the class specified which is of highly simplified construction, neat in appearance, and cheap to manufacture.

Other objects and advantages will be apparent during the course of the following description.

In the accompanying drawing forming a part of this application and in which like numerals are employed to designate like parts throughout the same,

Figure 1 is an end elevation of the receptacle closed;

Figure 2 is a side elevation of the receptacle, parts being broken away to show the rolling pin therein;

Figure 3 is a fragmentary detail sectional view through the receptacle illustrating the locking means embodied in the invention;

Figure 4 is a fragmentary sectional view through the receptacle in its open position.

In the drawing, wherein for the purpose of illustration is shown a preferred embodiment of the invention, the numeral 5 designates an elongated casing which may be either rectangular or cylindrical in cross-section, and which may be installed or built in a kitchen cabinet, a wall, or other support.

Secured to the forward end of the casing 5 in any suitable manner is a face plate 6 adapted to extend beyond the sides of the casing and form a projection or flange 7 of rectangular formation extending entirely about the casing. To one side of the flange 7 is hingedly connected, as indicated at 8, a door 9 for closing the front end of the casing. The opposite side of the flange 7 is provided with a slot 10 through which the outer terminal portion of a trigger or lever 12 slidably extends.

Figure 4 clearly illustrates that one side

of the casing 5 is grooved and slotted as 14 indicated at 14 for the reception of the trigger 12 whereby the forward end of the trigger may engage the adjacent end of a rolling pin 15. Connected to the trigger 12 intermediate the ends thereof is one end of a coil spring 16, the other end of the spring being connected to a stud pin 17 carried by one side wall of the casing adjacent the face plate 6. It will readily be seen that a constant outward pull will be exerted on the trigger 12 through the medium of the spring 16. It is desired to state at this point that the rear wall of the slot 14 is in the path of travel of and is adapted to be engaged by the inner end of said locking lever to limit the inward longitudinal movement of said lever.

The trigger 12 is provided in the inner edge thereof with a notch having a straight wall 18 and an inclined or beveled wall 20, which notch is adapted to receive a second stud pin 22 carried by one side wall of the casing. The outward longitudinal movement of the trigger 12 is limited by the straight wall 18 of the notch, while the inclined wall 20 serves as a means for removing the trigger from engagement with the adjacent end of the rolling pin 15 when the trigger is pushed inwardly by the operator. The rolling pin will also be moved inwardly until the trigger 12 becomes disengaged from the adjacent end thereof.

The notch of the trigger 12 is held in firm engagement with the stud pin 22 by a curved leaf spring 25, the rear end of which is rigidly connected to one side wall of the casing through the medium of suitable fastening devices. The spring 25 also holds the trigger 12 in the slot 14 at all times.

Rigidly secured to the bottom wall of the casing at the rear end thereof, as indicated at 27, is a suitably stout coil spring 28 tapering toward its forward end. By reference to Figs. 3 and 4, it will be seen that the spring 28 is adapted to encircle the adjacent handle of the rolling pin 15 and engage and exert a constant outward pressure on the forward end of the rolling pin whereby the rolling pin is urged into constant engagement with the trigger 12. The spring 28 also forms a means whereby the rolling pin 15 is ejected to partly ex-

posed position upon the release of the trigger 12 where it may be conveniently grasped by one's hand.

The operation of the device may be briefly summarized as follows:

- 10 The door 9 is first opened and the rolling pin inserted and pushed inwardly against the tension of the spring 28 until the rear end of the body portion has cleared the trigger 12 whereupon the trigger is automatically engaged with the adjacent end of the rolling pin and the same is thereby confined in place between the trigger 12 and the spring 28.
- 15 When it is desired to remove the rolling pin for use, it is merely necessary to exert an inward pressure upon the outer end of the trigger 12 which pressure will result in an inward longitudinal movement of the trigger 12 and the rolling pin and by reason of the inclined or beveled wall 20 of the notch in the trigger, the trigger is removed from engagement with the rolling pin, whereupon the rolling pin is partly ejected 25 by the spring 28 so that it may be completely removed by the operator.

From the foregoing it will be apparent that a receptacle constructed in accordance with this invention will provide simple and 30 convenient means whereby a rolling pin will be maintained in a strictly sanitary condition when not in use and which is readily accessible when its use is called for.

Having thus described the invention, what 35 is claimed is:—

1. A rolling pin receptacle comprising a casing having a closure and side walls, one of the side walls of said casing being provided with a slot, a lever extending through 40 said slot and engaging the adjacent end of a rolling pin within said casing for locking the same in place, and means for moving the rolling pin to partly exposed position upon the inward longitudinal movement of said lever.
2. A receptacle comprising a casing, a locking lever fulcrumed to the casing and having means whereby the same is urged into engagement with an article within the 50 casing to hold the same in place, and spring means housed within one end of the casing for ejecting said article to partly exposed position upon the manual inward longitudinal movement of said locking lever.
- 55 3. A receptacle comprising a casing provided with a slot, a lever extending through

said slot and engaging an article within said casing for locking the same in place, and means for removing said lever from engagement with said article upon the manual 60 inward longitudinal movement of the lever.

4. A rolling pin receptacle comprising a casing provided with a slot, a longitudinally movable locking lever having a notch provided with straight and inclined walls extending through said slot and engaging a rolling pin within said casing for holding the same in place, a pin carried by the casing and engaged with said notch, said inclined wall of the notch together with 70 said pin forming a means whereby the locking lever is removed from engagement with said rolling pin upon the manual inward longitudinal movement of the lever.

5. A rolling pin receptacle comprising a casing provided with a slot, a longitudinally movable locking lever having a notch provided with straight and inclined walls extending through said slot and engaging a rolling pin within said casing for holding the same in place, a pin carried by the casing and engaged with said notch, said inclined wall of the notch together with said pin forming a means whereby the locking lever is removed from engagement with said 80 rolling pin upon the manual inward longitudinal movement of the lever, the straight wall of said notch constituting a means whereby the outward longitudinal movement of the locking lever is limited.

6. A rolling pin receptacle comprising a casing provided with a slot, a longitudinally movable locking lever having a notch provided with straight and inclined walls extending through said slot and engaging a rolling pin within said casing for holding the same in place, a pin carried by the casing and engaged with said notch, said inclined wall of the notch together with said pin forming a means whereby the locking lever is removed from engagement with said rolling pin upon the manual inward longitudinal movement of the lever, the straight wall of said notch constituting a means whereby the outward longitudinal movement of the locking lever is limited, the rear wall of said slot being in the path of travel of and adapted to be engaged by one end of said lever to limit endwise movement of the lever in one direction.

In testimony whereof I affix my signature.
ELMER E. LANDON.
